UNITED STATES PATENT OFFICE.

ABRAHAM A. BROWN, OF NEW YORK, N. Y., ASSIGNOR TO SANITARY METHOD CO. INC.

TROUSERS.

1,126,379.

Specification of Letters Patent.

Patented Jan. 26, 1915.

Application filed April 21, 1914. Serial No. 333,388.

To all whom it may concern:

Be it known that I, ABRAHAM A. BROWN, a citizen of the United States, and a resident of the city of New York, borough of Brooklyn, in the county of Kings and State of New York, have invented a new and Improved Trousers, of which the following is a full, clear, and exact description.

This invention relates to alterable ready-made trousers and has to deal more especially with the waist construction whereby the trousers can be easily and quickly altered as to the waist measurements without requiring any special skill or necessitating the piecing out of the waistband lining and stiffening strips.

The invention resides more particularly in the back seam of a pair of trousers at the waist portion, in connection with a waistband lining of the character disclosed in my Patent Number 1,089,815, of March 3rd, 1914, the advantages being that the back seam can be readily opened to obtain the proper waist dimensions, and then sewed up again as a permanent seam and thereby comfortably fit the body of the wearer.

The objection with ready-made trousers having a waist lining of the usual construction, is that the alteration of the size of the waist is an extremely difficult operation, and besides it destroys the neatness of the finish, since the waistband lining and the stiffening material thereof has to be cut and pieced, especially when the waist of the trousers must be enlarged. With the construction herein set forth the waistband lining and reinforce is continued to the very edge of the cloth that forms the back of the trousers, so that in sewing the back seam the stitches pass through the waistband lining as well as the garment material, and the edges of the seam are then pressed back and sewed to the waistband lining. To make alterations it is merely necessary to rip the stitching of the seam, as well as the stitching that fastens the free edges of the material to the waistband lining, so that the seam can be let out to the proper dimensions, and then the seam is again sewed up and the free edges of the material stitched to the waist lining, leaving a seam which is as neat as the original seam and requiring no special skill in its production. The making of the seam, as well as the sewing of the waistband lining to the trousers, is done entirely by machine, so that the cost of manufacture is minimized

and the necessity of placing the trousers out to piece workers where unsanitary conditions usually prevail is avoided.

For a more complete understanding of the invention reference is to be had to the accompanying drawing which illustrates one embodiment of the invention and wherein similar characters of reference indicate corresponding parts in all the views, in which—

Figure 1 is a perspective view of the upper portion of a pair of trousers, showing the back seam in original condition; Fig. 2 is a similar view showing the back seam open for the purpose of making alteration; Fig. 3 is a perspective view of the waist portion of a pair of trousers showing the seam let out to increase the size of the waist; Fig. 4 is a perspective view showing the manner in which the back seam is made; Fig. 5 is a sectional view on the line 5—5, Fig. 4; Fig. 6 is a sectional view on the line 6—6, Fig. 1, before the alteration is made; Fig. 7 is a sectional view on the line 7—7, Fig. 3, after the alteration is made; and Fig. 8 is an enlarged vertical section on the line 8—8, Fig. 1.

Referring to the drawing, A and A' designate the upper portions of the leg sections of a pair of trousers which are provided with a waist lining made in two parts B and B', and attached to the sections A and A', respectively, to form a finish for the interior thereof. Each lining extends from the front edge of its respective section to the back edge. The lining includes, as shown in Fig. 8, a strip of stiffening material 4 and a soft lining material 2 which has its bottom edge 3 secured to the stiffening material and extends upwardly therefrom and is fastened to the material of the garment at 4. The lining material and stiffening strip are secured to the body of the trousers by a horizontal row of stitching 5, which row is covered by a flap 6 formed horizontally in the lining material 2. The rear ends of the waist lining 2 are secured to the edges 6^a of the sections A and A' by stitches 7, as shown in Fig. 4. After the lining is thus secured, the sections A and A' are placed together and fastened by a vertical line of stitching 8, whereby the flaps 10 and 10^a of the two sections are then flattened out from the position shown in Fig. 5 to that shown in Fig. 6, and the edges 11 of these flaps are bound to the lining B and B' by stitches 12, Fig. 1, so that a neat finish is obtained. It will be

noted that the under sides of the flaps 10 are faced by the terminal portions of the waist lining B and B', so that when alterations are required it is unnecessary to do any cutting whatsoever, and it remains merely to cut the stitches 8 so as to open the seam 9 as shown in Fig. 2, and then the binding stitches 12 are severed so that the seam can be closed at the required point, according to the waist measurement desired. If the trousers are to be enlarged in waist measurement, the seam 9 is closed near the edges of the flaps 10 by re-stitching the seam. After the back seam is completed, the edges of the flaps 10 are bound down by the stitches 12, as shown in Fig. 3. The original seam is shown in cross-section in Fig. 6, and after alteration is made the seam will appear as shown in Fig. 7, which presents as neat a finish as did the original seam, and the fabric is in no manner weakened, as the waistband has not been cut or pieced out. The alteration of ready-made trousers in this manner is a material advantage to merchants, as no special skill is required on the part of the alterer, and, besides, the alteration can be done with great despatch.

Having thus described my invention, I claim as new and desire to secure by Letters

30 Patent:

1. A pair of trousers comprising leg sections, a waistband lining extending to the back edges of the said sections, a seam located inwardly from the back edges of the

said sections to connect the latter together 35 and forming flaps of the edge portions of the said sections, and stitches securing the free edges of the flaps to the lining.

2. Trousers including leg sections, a waistband lining on each section and extending 40 to the rear edge thereof, and a line of stitching securing the said sections together and passing through the linings, the edges beyond the stitching forming flaps of extra material for permitting the waist of the 45 trousers to be enlarged by changing the position of the seam.

3. Trousers comprising leg sections, a stiffened lining for each section and extending from the front to the rear edges, the upper edge of each lining being secured to its respective section, and a row of stitching passing through the lining and through its respective leg section, and the lining including a flap to cover such row of stitching, 55 a line of stitching securing the rear edges of the leg sections together and passing through the complete lining of the respective sections, and stitching binding the back edges of the leg sections to the linings. 60

In testimony whereof I have signed my name to this specification in the presence of two subscribing witnesses.

ABRAHAM A. BROWN.
